(57) **CLAIM**

The ornamental design for the water fountain, as shown and described.

DESCRIPTION

FIG. 1 is a front perspective view showing my new water fountain design;

FIG. 2 is a front elevational view thereof;

FIG. 3 is a left side elevational view thereof;

FIG. 4 is a right side elevational view thereof;

FIG. 5 is a back elevational view thereof;

FIG. 6 is a top plan view thereof;

FIG. 7 is a bottom plan thereof; and,

FIG. 8 is front perspective view of my invention connected to a water supply hose in water, with ornamental boats mounted thereon.

The broken lines are for environmental purposes only and form no part of the claimed design.
